SECTOR CONTROL FOR TABULATING MACHINES.

1,423,439.

Specification of Letters Patent.

Patented July 18, 1922.

Application filed April 3, 1918. Serial No. 226,499.

To all whom it may concern:

Be it known that I, WILLIAM W. LASKER, a citizen of the United States, residing in Brooklyn, in the county of Kings and State of New York, have invented certain new and useful Improvements in Sector Controls for Tabulating Machines, of which the following is a specification.

This invention relates to improvements 10 in printing accounting machines, these improvements being applied to accounting machines having registering and printing elements comprising type sectors and reciprocating rack bars positively driven for operating the type sectors. Such a machine is described in detail in my co-pending application Serial No. 158,142, filed March 28th, 1917; and, therefore, only the parts of such machine are herein described as are necessary for an understanding of the new improvements.

In said machine the type are mounted upon arcuate sections of the type sectors and are driven by intermeshing rack bars. 25 As the type upon said sectors render one side of the sector heavier than the other, there is a tendency of the type sector and the associated rack bar, to move in a retrograde direction after they have been moved forwardly to printing position. One object of 30 the present invention is to provide improved and efficient means for preventing this result.

In said machine, each of the rack bars is 35 provided with a depressible abutment lever provided with an abutment against which engages a transverse reciprocating bar for positively driving the bars and the type sectors to total taking position, the accumulating 40 wheels which mesh with the type sectors being provided with projections adapted to engage a part for depressing said abutment levers for disengaging them from said transverse bar when total taking position is 45 reached. Another improvement herein, has for its object to provide an improved part for accomplishing this last named result.

These and other objects will appear as the description proceeds; and while herein I 50 have described minute details of the invention, the invention is not limited to these, since the details of construction and combination may be greatly varied without departing from the spirit and scope of the invention as claimed.

In the accompanying drawing showing by way of example one of the many possible embodiments of the invention,—

The figure is a longitudinal vertical sectional view through the printing and accounting machine, showing in side elevation the parts necessary for a proper understanding of the present invention.

In the said co-pending application means are shown for feeding perforated cards to an analyzer comprising a reciprocating pin box provided with pins adapted to feel the cards and on finding perforations therein, to pass therethrough to raise registering stop pins corresponding to the perforations 65 corresponding to numerals, the naught stop being normally raised and adapted by suitable connections to be depressed by the raising of the numeral stop pins.

In the present specification, the left hand 70 end of the machine, as shown in the figure, is considered the forward end of the machine.

Referring more particularly to the drawing of the present specification, there is 75 shown one of the cheek plates 10, between which cheek plates the various mechanisms of the accounting machine are mounted, these cheek plates being carried on a suitable base or frame not shown. Between said 80 cheek plates there are mounted a plurality of rows of numeral stop pins 11 vertically 85 slidable in upper and lower guide-plates 12, carried upon cross-plates 13 mounted upon the cheek plates. Each numeral stop pin is 90 provided at its upper end with a head 15 provided at its rear part with a vertical face 16 and at its forward part with an inclined face 18. The lower part of each pin is provided with an elongated recess 19 in which 95 engages one of the projections 20 carried on the restoring lever 21, fulcrumed at its forward end upon a shaft 22 carried by said cheek plates. The rear end of the restoring 100 lever is pivotally connected to one end of a lever 24 of the first order which is intermediately fulcrumed on a rod 25 mounted in the cheek plates 10 and has its other end loosely pivotally connected to the zero stops 26 vertically slidable in the guide plates 12 105 and disposed just to the rear of the respective rows of pins 11.

By this means whenever a numeral pin 11 is raised the lower part of the recess 19 engages one of the projections 20 and 110

causes the lowering of the zero stop 26, the zero stop being normally raised.

Associated with each row of stop pins 11 is a shutter 28 adapted to engage in a recess in the side of the stop pin to hold the same in raised position and at the proper time to release the pins; but these are fully explained in said co-pending application and need not be further described here.

- 10 Slidably disposed above each row of pins 11 is a reciprocating rack bar 30 guided in a pair of comb plates 31, and on a rod 32 mounted in the cheek plates and received in a slot 34 in the rear part of the rack bar. On the rear of each rack bar is provided an upturned standard 35 on the upper end of which is pivotally mounted a holding pawl 36, the object of which will be presently explained.
- 20 The forward part of the upper edge of each rack bar 30 is provided with a series of teeth 38 adapted to mesh with a gear wheel 39 fixed upon the side of each type sector 40 rotatably mounted upon the 25 sector shaft 41, each sector is provided with a series of printing type 42 and a series of gear teeth 43 adapted to engage with the accumulator wheels 44.

Against one side of each rack bar 30 there is disposed an abutment lever 50 pivoted at its forward end to the rack bar and extending rearwardly along said rack bar above said rod 32. A spring 51 strained between the rear end of the rack bar and the forward end of the pawl 36 holds the rear end of the abutment lever and the rear end of the holding pawl normally in raised position. In the figure the abutment lever is shown in depressed position.

- 40 The intermediate part of the abutment lever is slightly laterally offset forming a space for the reception of a tripping elbow lever 54 pivotally fulcrumed at its elbow part to the side of the rack bar 30 and provided at its forward end with a lateral projecting pin 55 engaging in a small longitudinal slot 56 in the abutment lever. The lower end of the elbow lever is provided with a laterally turned end forming an inclined face 58 and a forward shoulder 59. The rack bar 30 is provided with an upstanding abutment provided with a forwardly disposed shoulder 60, which when the abutment lever is raised, is opposed to 55 and slightly spaced from the rearwardly disposed shoulder 61, formed by an upstanding abutment on the abutment lever. Between said shoulders is disposed a reciprocating rack bar 62 which is reciprocated forward and backward by suitable means controlled by a suitable cam control means, as explained in said copending application. When the transverse bar 62 is retracted, it 60 engages the shoulder 60 and retracts the 65 rack bars, the abutment levers and the el-

bow levers, whereupon said inclined face 58 engages the forwardly inclined forward face 64 of the zero stop 26 and permits the shoulder 59 to engage the rearwardly and downwardly inclined upper rear face 65 of the zero stop. When the transverse bar 62 commences its forward movement, the shoulder 61 is in raised position and is engaged by the transverse bar. If at this time the naught stop is in raised position the shoulder 59 presses upon the steeply inclined rear face 65 of the naught stop and causes the elbow lever to be rocked and the pin 55 to be lowered, whereupon the transverse bar 62 is freed from the rearwardly disposed shoulder 61, thus permitting the transverse bar 62 to move forwardly without carrying forward the rack bar. If, however, in accordance with the perforations of the card being analyzed, one of the numeral 85 stop pins 11 has been raised and the zero stop lowered, the elbow lever passes over the lowered zero stop without being rocked, whereupon the shoulder 61 remains raised and in contact with the transverse bar 62 90 until the shoulder 59 of the elbow lever comes into contact with the rear face 16 of the head 15 of the raised stop pin 11, whereupon the elbow lever is rocked and the transverse bar 62 is freed and passes on to 95 complete its cycle of movement. This forward movement of the rack bar rocks the type sector 40 and brings the type 42 corresponding to the raised stop pin in front of the reciprocating printing carriage, conventionally shown and indicated by reference numeral 68, whereupon as described in said co-pending application, the printing carriage 68 is moved toward the type and presses the paper carried thereon against 100 the type and prints the number corresponding to the raised pin.

The rear face 65 of the zero stop is made steeply inclined, whereby when the rack bar 30 is retractive enough to carry the shoulder 110 59 to the rear of the zero stop it will surely snap behind the zero stop and engage said inclined face.

Since, as is obvious by an inspection of the figure, the part of the type sector carrying the type is more remote from the center of the type sector than the other parts thereof, the weight of this part tends after the transverse bar 62 has been freed, to cause the type segment to assume a movement 120 which is anti-clockwise in the figure. Means for preventing this anti-clockwise movement will now be described.

Between the rear part of the cheek plates 10, there is disposed a vertically movable 125 inverted U-shaped bracket 70 having down-turned arms 71 slidably engaging the inner face of the cheek plates. These arms are guided in their movement at their upper part by means of a transverse rod 72 passing 130

entirely across the machine and through said arms and engaging in slots 73 provided in the cheek plates. The lower ends of said arms are provided with elongated slots 74 receiving pins 75 projecting from the inner face of the cheek plates, whereby the lower ends of said arms are guided in their movement. The yoke 76 of the bracket 70 has fixed thereto a horizontal ratchet plate 77 provided in its lower face with ribs disposed transversely of the machine and providing inclined rear faces 78 and forward vertical faces 79. This ratchet plate and the bracket 70 remain in their lower position while the rack bar 30 is moved forwardly under the action of the transverse bar 62 during which time the rear end of the pawl 36 cams over the inclined faces and when the transverse bar 62 is freed the rear end of the pawl 36 engages the vertical face 79 and prevents any retrograde movement of the rack bar or the type sector.

Before the transverse bar 62 on its return movement retracts the rack bars, it is necessary to raise the ratchet plate 77 out of engagement with the pawl 36, and this is accomplished by means of the mechanism which will now be described.

The fact that the ratchet plate 77 is common to all of the pawls 36 permits a slight lateral movement of the pawl, in machines where the pawls and rack bars are very thin, without the pawls becoming out of register with the ratchet plate.

35 The down-turned ends 71 of the inverted bracket are provided with inwardly projecting lifting pins 81 received in the slotted rear end of the lifting lever 82 intermediately fulcrumed on the cheek plate and having its forward end connected by means of a link 83 with the rear end of an intermediate lever 84 also intermediately fulcrumed on the cheek plate and which has its forward end pivotally connected to a cam lever 85 intermediately fulcrumed to the cheek plate as at 86 and provided at its forward end with a roller 88 engaging in a cam slot 89 provided in the cam 90 mounted upon the cam shaft 91 suitably supported on the frame of the machine. This cam is so timed and the cam groove is so designed, that the ratchet plate 77 is raised out of contact with the pawl 36 before the transverse bar 62 retracts the rack bars.

55 After the type segments have been positioned by a forward movement of the rack bar and before the ratchet plate has been raised to permit their rearward movement, said type sectors are locked and aligned in position by means of the engagement, between the teeth 43, of a locking bar 95 slideable in slots 96 provided in the cheek plates and reciprocated by means of a link 98 having its upper end secured to the locking bar 65 and having its bifurcated lower end 99 strad-

70 dling the cam shaft 91 whereby said link is guided. Reciprocatory movement is imparted to the link by means of the engagement of a roller 100 mounted on the link and engaging in the cam groove 101 provided in a suitable cam wheel carried on the cam shaft 91. This cam groove 101 is so designed that the type sectors are locked in place after they have been positioned by the rack bars and are held locked during the 75 time the printing takes place and until the ratchet plate 79 is raised, but are released before the transverse bar 62 engages the shoulder 60 in its rearward movement.

75 Between the main cheek plates 10 there is 80 slidably mounted behind the type sectors 40, the reciprocating accumulator carriage 105 provided with a shaft 106 on which are mounted the accumulator wheels 44 provided with teeth adapted to mesh with the gear teeth 43 of the type sectors. Fixed to the side of each accumulator wheel is a collar 109 provided opposite the zero tooth of the accumulator wheel with an inclined projection providing an inclined rear face 110 90 and a radial forward face 111. Diametrically opposite said projection, each collar is provided with a curved projection 112.

A complete description of the construction and operation of the reciprocating accumulator carriage and the means for reciprocating it, is given in said co-pending application. The lever 114 and the cooperating parts at the lower left hand corner of the figure relate to the means for reciprocating the accumulator carriage but are not described herein. The accumulator carriage is, during accumulation, reciprocated in such a manner that when the rack bars are moving forward, to position the type sectors, the accumulator 100 wheels are out of mesh with the type sectors; but when the type sectors are returning to their normal position, the accumulator 105 wheels are in mesh with the type sectors and are each rotated a distance determined by the position in which the associated type sector was set. When the accumulator 110 wheels are set at zero, said radial face 111 engages behind the lower end 115 of the horizontal lever 116 of the accumulator carriage. During accumulation the accumulator 115 wheels are moved in a direction which is clockwise on the figure of the drawing, and when the accumulator wheel has made a complete revolution the inclined face 110 engages the forward face of said lower end 115 of the horizontal lever which as explained in said co-pending application, causes the lowering of the kick-back device 117 at the lower part of the accumulator carriage 125 which kicks back against the forwardly disposed shoulder 60 of the rack bar 30 the distance of one tooth of the accumulator wheel which effects the carrying.

120 This takes place after the rack bars have 130

been retracted to their rear position in which position the rear end of the pawl 36 is behind the rearmost rib of the ratchet plate and does not in any way interfere with this kick-back of the rack bar.

When a total is to be taken the zero stops are lowered by suitable mechanism as described in said copending application. This lowering, because of the length of the recesses 19 does not raise the pins 11, whereby the shoulders 59 of the elbow levers are not obstructed when the rack bars move forwardly.

When a total is to be printed, the reciprocating mechanism of the accumulator carriage operates to bring the accumulator wheels into mesh with the type sectors when the bar 62 is traveling forwardly. In this case the zero stop 26 and the pins 11 are lowered, the forwardly disposed shoulder 61 is in raised position and the rack bars are carried forward by the transverse bar 62 until the radial face 111 of the accumulator wheels engages the rear face of the lower end 115 of the horizontal lever 116. When this takes place the curved projection 112 engages with a roller 120 rotatably mounted upon a vertically slidable bracket 121 and bears against the top edge of the associated abutment lever 50. The brackets 121 are provided with vertical slots 122, receiving transverse rods 123 mounted upon the cheek plates 10 of the machine whereby vertical movement is permitted to the brackets and the rollers carried thereon. When the rounded projection 112 engages the rollers as just explained and lowers the abutment lever, the rearwardly disposed shoulder 61 of the abutment lever is lowered and permits the transverse bar 62 to pass on forwardly leaving the rack bars as positioned by the abrupt shoulder 111 of the accumulator wheels.

From the foregoing operation the new improvements will be readily understood and need now be only briefly summarized as follows:

As the perforated cards are fed through the machine, for each column either a zero stop 26 is left raised or one of the pins 11 is raised and the zero stop 26 is lowered for each column of the card. At this time the abutment lever is raised, the reciprocating transverse bar 62 is in its rear position of movement, and the rearwardly disposed shoulder of the abutment lever is disposed in front of the transverse bar. The transverse bar then moves forwardly until the shoulder 59 of the elbow lever is forced into contact with the rear face of the raised stop 26 or pin 11, thus forcing down the abutment bar and the rearwardly disposed shoulder 61 and permitting the transverse bar 62 to travel free. Any movement of the rack bar which has then taken place is de-

termined by the position of the pin or zero stop then raised, and this movement is communicated to the type sector whereby the type is positioned for printing. As this forward movement of the rack bars takes place 70 the pawl 36 engages the faces 79 of the ratchet plate and prevents any retrograde movement of the rack bars or the type sectors after the transverse bar 62 has been freed. Before the printing takes place the 75 locking and alining bar 95 engages between the teeth 43 and holds the type sectors locked and alined while the printing carriage 68 forces the paper against the type. After the printing takes place the transverse 80 bar 62 commences its rearward movement and before it has engaged the forwardly disposed shoulder 60, the locking and alining bar 95 is moved out of contact with the teeth 43 and the ratchet face 79 is raised out of 85 contact with the pawl 36 whereby the rack bars may be retraced by the transverse bar 62 engaging the shoulder 60. When a total is taken the zero stop 26 is lowered by means described in said co-pending application; 90 and because of the length of the recesses 19 in the lower part of the pins 11 this lowering of the zero stop may take place without raising the stop pins. Therefore, when the reciprocating rack bar moves forwardly for 95 taking the total, the zero stop and all of the pins 11 are lowered and the rack bars may move forwardly without any engagement of the elbow levers with the pins 11 or stop 26. At the beginning of the forward movement 100 of the transverse bar 62, the abutment levers 50 are held raised by means of the spring 51 until the accumulator wheels which are all then in mesh with the type sectors, turn in anti-clockwise direction until the abrupt shoulder 111 of the accumulator wheels engages the lower end 115 of the horizontal lever. At this instant, the rounded projection 112 engages the roller 120 and permits the transverse bar 62 to 105 pass on free.

Should it for any reason happen that the rack bars move rearwardly while an abutment lever is raised and a stop pin 11 or zero stop 26 is also raised, the inclined 110 lower face of the elbow lever 54 merely cams over an inclined forward face 18 of a pin 11 or an inclined forward face 64 of a zero stop 26. In this way injury to these parts is prevented.

I claim as my invention:

1. In an apparatus of the character described, the combination of character carriers; means for preventing retrograde movement of the carriers and comprising a 125 device associated with each carrier, and a single device engaged part common to all of the devices; and means for moving the single engaged part out of the path of the devices.
2. In an apparatus of the character de- 130

scribed, the combination of character carriers; means for preventing retrograde movement of the carriers and comprising a device mounted on each carrier, and a single 5 device engaged part common to all of the carriers; and means for moving the engaged part out of the path of the devices.

3. In an apparatus of the character described, the combination of character carriers; means for preventing retrograde movement of the carriers and comprising a pawl mounted on each carrier, and a single 10 pawl engaged part; and means for moving the engaged part out of the path of the 15 pawl.

4. In an apparatus of the character described, the combination of actuating members, character carriers controlled by the members; a holding pawl on each member; 20 a pawl engaged part adapted to be engaged by said pawls; and means for moving said part into or out of the path of the pawl.

5. In an apparatus of the character described, the combination of rows of vertically 25 movable pins; a reciprocating bar associated with each row; type carriers controlled by the reciprocating bars; a holding pawl mounted on each reciprocating bar; a ratchet plate adapted to be engaged by said 30 pawls to hold the reciprocating bars and carriers from retrograde movement; and means for moving the ratchet plate into or out of the path of the pawls.

6. In an apparatus of the character described, the combination of reciprocating 35 bars; type sectors controlled by the bars; a pawl on each bar; a ratchet plate adapted to be engaged by the pawls; and means for moving the ratchet plate away from the 40 pawl.

7. In an apparatus of the character described, the combination of rows of vertically 45 movable pins; a reciprocating bar associated with each row; type sectors controlled by the reciprocating bars; a holding pawl pivoted to the rear part of each reciprocating bar; a vertically 50 movable horizontally disposed ratchet plate adapted to be engaged by said pawls to hold the reciprocating bars and type 55 sectors from retrograde movement; a cam operated part operatively connected to said ratchet plate; a cam engaging said part for lowering the ratchet plate when the reciprocating bars are retracted and means controlled by said pins for moving said reciprocating bars forwardly.

8. In an apparatus of the character described, the combination of rows of vertically 60 movable pins; a reciprocating bar above each row and provided with a forwardly disposed shoulder; type sectors and accumulating means controlled by said bars; an abutment lever pivoted to each bar and provided with a rearwardly disposed shoulder; opposing the forwardly disposed shoulder;

a tripping lever fulcrumed to each reciprocating bar and connected to the abutment lever and adapted to engage behind any raised pin whereby the abutment lever is lowered as the reciprocating bar moves forwardly; a holding pawl pivoted to the rear part of each reciprocating bar; means for holding the rear part of said pawl slightly raised and said abutment lever yieldably raised; a vertically movable horizontally disposed ratchet plate disposed above said pawls and provided with transverse ratchet ribs having abrupt shoulders and inclined rear shoulders, said ribs being adapted when the ratchet plate is lowered to be engaged 70 by said holding pawl to prevent retrograde movement of the type sectors; a lifting lever operatively connected to the ratchet plate; a cam lever operatively connected to the lifting lever; a cam wheel provided with a 75 groove engaging said cam lever and so shaped that said ratchet plate is raised out of contact with the holding pawls while the rack bars are being retracted; and a transverse reciprocating bar adapted to be disposed between said shoulders for reciprocating the reciprocating bars.

9. In an apparatus of the character described, the combination of a plurality of rows of vertically movable pins; a zero stop 80 vertically and slidably disposed at the rear of each of said rows; a longitudinally disposed reciprocating rack bar above each row and provided with a rearwardly disposed shoulder, and at its rear end with an upturned standard; a holding pawl intermediately pivoted on the upper end of said standard; an abutment lever pivoted to each rack bar and provided with a rearwardly disposed shoulder adapted, when the abutment lever is raised to oppose said forward disposed shoulder; a spring tensioned between the forward part of said pawl and the rear part of said abutment lever, whereby the rear part of said pawl is normally 85 slightly raised and said rearwardly disposed shoulder is normally raised to oppose said forwardly disposed shoulder; a transverse reciprocating bar disposed between the opposed shoulders; an elbow lever fulcrumed 90 on each rack bar and having its forward part connected to said abutment lever and its lower end provided with a shoulder adapted to engage behind said zero stop or any raised associated pin whereby when the rack bar is moved forwardly the rack bar is stopped and the abutment lever is lowered to 95 continue forwardly; type sectors and accumulating means operated by said rack bars; an inverted U-shaped bracket vertically 100 movable near said standards; a ratchet plate mounted upon the yoke of said inverted bracket and provided with transverse ratchet ribs having abrupt front shoulders and inclined rear shoulders, said ribs being adapt-

105 110 115 120 125 130

ed, when the ratchet plate is lowered to be engaged by said holding pawl to prevent retrograde movement of the type sectors; a lifting lever pivotally connected to said bracket; a cam lever provided with a cam engaging roller and operatively connected to the lifting lever; and a cam wheel provided with a groove receiving said roller and so shaped that said ratchet plate is raised out of contact with the holding pawls while the rack bars are being retracted.

10. In a device of the character described, the combination of accumulators; means for positioning the accumulators; means for driving the positioning means for positioning the accumulators; and means operated by the accumulators for rendering the connection between the positioning means and the driving means inoperative when the total 20 indicating position is reached.

11. In a device of the character described, the combination of accumulators; means for positioning the accumulators; means for driving the positioning means for positioning the accumulators; and rollers operated by the accumulators for rendering the connection between the positioning means and the driving means inoperative when the total indicating position is reached.

12. In a device of the character described, the combination of accumulating means; means for positioning the accumulating means comprising a movable part; means for engaging said movable part for positioning the accumulating means; and a roller adapted to be engaged by the accumulating means for pushing said movable part out of the path of said driving means when the accumulator is in total indicating position.

13. In a device of the character described, the combination of accumulating wheels provided with projections; means for stopping the accumulating wheels in zero position for indicating totals; means for positioning the accumulator wheels and provided with depressible devices; means engaging behind said depressible devices for driving the positioning means; and a roller adapted to be engaged by said projection for depressing said depressible device.

14. In an apparatus of the character described, the combination of a plurality of type carrying means; means for positioning said type carriers comprising a depressible device provided with an abutment shoulder; accumulating means connected with the type carrying means and provided with a projection; means for stopping the accumulating means in position to print totals; means adapted to be engaged by said projection for depressing said depressible means; and means for engaging said shoulder and driving said positioning means until the depressible device is depressed.

15. In an apparatus of the character de-

scribed, the combination of a plurality of type sectors; selecting bars operatively connected to each type sector; an abutment lever carried by each selecting bar and provided with a shoulder; a transverse bar adapted to engage behind said shoulder for driving the selecting bar and the type sector; selective means associated with each selecting bar for lowering the abutment lever when the desired position of the selecting bar and type sector is reached; accumulator wheels operatively connected to the type sectors and each provided with a projection; means for stopping said accumulator wheels in zero position when taking a total; and a roller disposed over each abutment lever and adapted to be contacted by the projection and to lower the abutment lever when the accumulator wheel is in zero position.

16. In an apparatus of the character described, the combination of rows of vertically movable pins; a longitudinally disposed rack bar above each row; an abutment lever pivoted to each rack bar and provided with a rearwardly disposed shoulder; a transverse reciprocating bar adapted to engage behind said shoulder when the abutment lever is raised; a tripping lever pivotally connected to said abutment lever and rack bar and adapted to engage any raised pin of the associated row for lowering the abutment lever; type sectors meshing with each rack bar; accumulator wheels adapted to mesh with said sectors respectively and each provided with a rounded projection; means for stopping said accumulator wheels in zero position when taking totals; and a vertically movable roller disposed above each abutment lever and adapted to be contacted by said projection and to lower the abutment lever when the accumulator wheel is in zero position, whereby the transverse bar is permitted to move forwardly.

17. In an apparatus of the character described, the combination of rows of vertically movable pins; a zero stop vertically movable at the rear of each of said rows; a longitudinally disposed reciprocating rack bar above each row and provided with a forwardly disposed shoulder; an abutment lever pivoted to each rack bar and provided with a rearwardly disposed shoulder adapted when the abutment lever is raised to be opposed to said forwardly disposed shoulder; a transverse reciprocating bar adapted to be disposed between said shoulders; an elbow lever fulcrumed at its elbow to each rack bar and having its forward end pivotally connected to said abutment lever and its lower end adapted to engage behind a raised pin or stop of the associated row whereby when said rack bar moves forwardly, the rack bar is stopped and the abutment lever is lowered to permit the transverse bar to

- be moved forwardly; type sectors meshing with said rack bars; a reciprocating accumulator carriage provided with accumulator wheels adapted to mesh with said sectors respectively; a collar secured to each accumulator wheel and provided with a rounded projection diametrically opposite to the zero tooth and with an inclined projection adjacent to the zero tooth and having an abrupt 5 forward shoulder; a lever having a hooked end adapted to engage and stop the accumulator wheel when taking totals; a vertical slideable bracket associated with each rack bar; and a roller carriage on each bracket 10 and rolling on the adjacent abutment lever and adapted to be contacted and depressed by the rounded projections of the associated accumulator wheel when the latter is stopped in the zero position during total taking, 15 whereby the transverse bar is freed.
18. In an apparatus of the character described, the combination of rows of vertically movable pins; a vertically movable zero stop at the rear of each row and provided 20 with a steeply inclined rear face; a reciprocating bar above each row and provided with a forwardly disposed shoulder; tabulating and accumulating means controlled by said bars; an abutment lever pivoted to 25 each bar and provided with a rearwardly disposed shoulder opposed to the forwardly disposed shoulder; a tripping lever fulcrumed to each reciprocating bar and connected to the abutment lever and adapted to 30 engage said inclined rear face or the rear face of any raised pin; and a transverse reciprocating bar disposed between said shoulders.
19. In an apparatus of the character described, the combination of rows of movable pins; a vertical movable zero stop at the rear of each row and provided with a steeply inclined rear face; a reciprocating bar above each row; accumulating means controlled by 35 said bars; an abutment lever pivoted to each bar and provided with a rearwardly disposed shoulder; a tripping lever connected to each bar and abutment lever and adapted to engage said inclined face or any raised 40 pin and thereby to lower said abutment lever; and means engaging behind said shoulders for driving said bars forwardly when the abutment levers are not lowered.
20. In an apparatus of the character described, the combination of a plurality of rows of vertically movable pins; a zero stop vertically and slidably disposed at the rear of each of said rows and provided with a steeply inclined upper rear face; a longitudinally disposed reciprocating rack bar above each row and provided with a forwardly disposed shoulder; an abutment lever pivoted to each rack bar and provided with a rearwardly disposed shoulder adapted, 55 when the abutment lever is raised, to be opposed to and slightly spaced from said forwardly disposed shoulder; a transverse reciprocating bar adapted to be disposed between said shoulders; an elbow lever fulcrumed on each rack bar and having one end 70 connected to the abutment lever and provided with a shoulder adapted to engage said steeply inclined rear face when the zero stop is raised, or to engage behind any raised associated pin whereby when the rack bar is moved forwardly the rack bar is stopped and the abutment lever lowered to permit the transverse bar to move forwardly; and tabulating and accumulating means controlled by said rack bars. 75
21. In an apparatus of the character described, the combination of a plurality of rows of vertically movable pins each provided with a forwardly beveled head; a zero stop vertically slidably disposed at the rear of each of said rows and provided with a downwardly inclined upper front face and a steeply inclined upper rear face; means for lowering the zero stop when one of the associated pins is raised; a longitudinally disposed reciprocating rack bar above each of said rows and provided at its intermediate part with an upstanding rearwardly disposed shoulder; an abutment lever disposed against each rack bar and having its forward end pivoted to the rack bar and its intermediate part provided with a slot and an upstanding rearwardly disposed shoulder spaced from and opposed to said forwardly disposed shoulder when the abutment lever is raised; means yieldably holding said abutment lever in raised position whereby said shoulders oppose each other; a transverse reciprocating bar adapted to be disposed between said shoulders when opposed; 105 an elbow lever fulcrumed at its elbow to each rack bar and provided at its forward end with a pin engaging in said slot and at its lower end with a forwardly and downwardly inclined lower face adapted to cam over any associated raised pin or zero stop as the rack bar moved rearwardly whereby said abutment lever is raised, said lower end being also provided with a shoulder being adapted to engage behind a raised pin or stop whereby when said rack bar is moved forwardly, the rack bar is stopped and the abutment lever is lowered to permit the transverse bar to move forwardly; and type sectors operated by said rack bar. 110
22. In an apparatus of the character described, the combination of a pair of cheek plates; a plurality of rows of vertically moving stop pins mounted between said cheek plates and each provided with a lower elongated recess and a forwardly and downwardly beveled head; a zero stop vertically slidably disposed at the rear of each row and provided with a forwardly and downwardly inclined upper front face and a steep 120

- 130

rearwardly and downwardly inclined upper rear face; a pivoted restoring bar associated with each row and provided with projections engaging in said recesses; levers of the 5 first order associated with each row and having one end pivoted to the zero stop and the other pivoted to said restoring bar whereby when any one of said pins is raised the associated zero stop is lowered; a longitudinally 10 disposed reciprocating rack bar above each of said rows and provided at its intermediate part with an upstanding abutment forming a forwardly disposed shoulder, and at the forward part of its upper edge with a plurality 15 of rack teeth; an abutment lever disposed against the side of each rack bar and having its forward end pivoted to the forward end of the rack bar and its intermediate part provided with an elongated slot and an up- 20 standing abutment having a rearwardly disposed shoulder spaced from and adapted, when the lever is raised, to be opposed to said forwardly disposed shoulder; means yieldably holding said abutment lever in 25 raised position, whereby said shoulders op-

pose each other; a transverse reciprocating bar disposed between the opposed shoulders; an elbow lever fulcrumed at its elbow to each rack bar between such rack bar and their associated abutment lever, and provided at its 30 forward end with the pin engaging in said slot and at its lower end with a forwardly and downwardly inclined lower face adapted to cam over any associated raised pin or zero stop as the rack bar moves rearwardly 35 whereby said elbow lever is rocked and the abutment lever raised, said lower end being also provided with a front shoulder adapted to engage behind a raised pin or stop as the rack bar is moved forwardly, whereby said 40 rack bar is stopped and the elbow lever rocked forwardly to lower the abutment lever to permit the transverse bar to move forwardly; and type sectors provided with gear teeth meshing with the teeth of the rack 45 bars.

WILLIAM W. LASKER.
